CLAIM

The ornamental design for a four side rails extended rifle mount, as shown and described in following figures.

DESCRIPTION

FIG. 1 is a top isometric perspective view of a four side rails extended rifle mount showing my present invention and embodiment;

FIG. 2 is a left view of FIG. 1

FIG. 3 is a right view of FIG. 1

FIG. 4 is a front view of FIG. 1

FIG. 5 is a rear view of FIG. 1

FIG. 6 is a top view of FIG. 1; and,

FIG. 7 is a bottom view of FIG. 1.
